(57) **CLAIM**

I claim the ornamental design for the sewing template, as shown and described.

DESCRIPTION

FIG. 1 is a top plan view of a sewing template of the present application;

FIG. 2 is a right-side elevational view thereof (a left-side elevational view thereof would be identical); and, FIG. 3 is a front elevational view thereof (a back elevational view thereof would be identical).

The broken lines shown in the drawings are included for the purpose of illustrating portions of the sewing template and form no part of the claimed design.
